UNITED STATES PATENT OFFICE

2,372,007

VACUUM SWEEPER CONSTRUCTION

Henry A. Kroenlein, Jackson, Mich., assignor to
The Filtek Corporation, Jackson, Mich., a corporation of Michigan

Application November 9, 1938, Serial No. 239,610

4 Claims. (Cl. 15—16)

The present invention relates to improvements in the construction of the so-called cylinder type vacuum sweeper; being especially concerned with the structural details of the vacuum sweeper disclosed in my design application Serial No. D-80,973, filed November 9, 1938, now Design Patent No. 113,531, granted February 28, 1939.

Objects of the present invention reside in the details of construction hereinafter set forth, and the combination and arrangement of parts which result in better appearance, improved performance, increased utility, and a reduction in the cost of manufacture. The invention is defined in the appended claims.

In the drawing,

Fig. 1 is a longitudinal cross-sectional view of the vacuum sweeper construction,

Fig. 2 is a fragmentary cross-sectional view of a modified mounting ring, and

Fig. 3 is a fragmentary cross-sectional view of the embodiment of Fig. 1 showing the tie rod assembly.

Referring to the drawing, the vacuum sweeper shown in Fig. 1 is a well known cylinder type generally designated by reference character 10 comprising front and rear heads 12 and 14 preferably of cast metal, and a central portion in the front of the hollow cylinder 16. For inexpensive construction, the cylinder 16 may be of fibrous tube construction with some suitable finishing surface such as imitation leather or the like. The opposite ends of the cylinder 16 telescope with cylindrical flanges 18 and 20.

Clamped between one end of the cylinder 16 and the shoulder 22 is a rubber mounting ring 24 which supports the air pump and motor unit 26. This unit which is floated free from the cylinder 16 and head 14, comprises a housing 28 with two stages of pumping, the centrifugal impellers 30 and 32 rotating as a unit relative to the fixed part 34 acting to return the air flow to a point adjacent the axis of rotation of the impeller 32 in a well known manner. Supported at the forward end of the housing 28 is a receiver 36 having a perforated wall 38 within which a filter pad is adapted to be inserted for filtering the air drawn through the open ended fabric collector bag 40. The bag 40 has a retainer ring 42 which is clamped between the head 12 and flange 18 at the time the former is hinged around the point 44 and locked in closed position by the fastener 46 engaging with the pin 48. A tapered intake opening 50 in the head 12 receives a similarly tapered metal ferrule in the end of the flexible conduit connection to the sweeper nozzle. 55

The unit 26 includes a bracket 52 which provides a bearing 54 for the shaft 56 and supported for the motor 58. A housing 60 is secured to the bracket 52 by screws 62 and closes one end of the unit 26 except for an outlet opening 64 corresponding to the intake opening 50. With the hinged closure 66 closing the opening 68 in the head 14, air from the outlet 64 will discharge into the chamber 70 and filter out through the openings 72. When the device is to be used as an air blower, a connector is fitted into the outlet 64 as shown in dotted outline, the closure 66 being hinged out of the way. The switch for opening and closing the motor circuit, preferably, takes the form of a depressible foot plate 74 hinged at 76 and resting against a push on and off switch 78 of well known construction.

The head 14, the cylinder 16, and the unit 26 are held in assembled relation through a pair of concealed tie rods 80 located upon opposite sides of the cylinder 16. The flange portions 18 and 20 have thickened bosses 82 and 84 in which opposite ends of the rods 80 are anchored. As shown, each rod 80 is threaded at 86 into a correspondingly threaded hole 88 in the boss 84. The opposite ends of the rods 80 are also threaded at 90 to receive a cylindrical nut 92 having a screw drive slot 94 therein. With the nut seated against the shoulder 96, rotation thereof will clamp the mounting ring 24 and the cylinder 16 firmly between the flange 18 and shoulder 22. It will be understood that the nuts 92 are tightened with the head 12 in a hinged position.

As I consider it desirable to have a resilient bumper entirely around the sweeper, I prefer to house the rods 80 in sections 98 of the rubber bumper which extend along the sides of the cylinder 16. Thus the rods 80 are covered by the bumper sections while functioning to support the same. The heads 12 and 14 have embracing channels 100 and 102 in which bumper sections 104 and 106 are supported. To secure these sections in place there is a wire core 108 which is tapped at opposite ends at 110 to receive anchoring screw 112.

In the modification of Fig. 2, the mounting ring 113 comprises a rubber ring portion 114 and an outer and inner metal ferrule portions 116 and 118. With this arrangement the entire support given the pump and motor unit is through the rubber body.

It should be apparent from the foregoing description that I have provided a very simple assembly. The tie rods 80 hold the major portion of the construction in an assembled relation in-

cluding the air pump and motor unit. With the head 12 in closed position, the tie rods 80 and associated structure are completely concealed. In addition, the rods function to support the bumper sections extending along the cylinder portion 16. Through the use of the tie rods 80 and the character of the reinforcement afforded by the parts with which the ends of the cylinder 16 telescope, the cylinder 16 may be inexpensively manufactured from a cardboard tube or the like making it possible to provide a vacuum sweeper of extremely light and rigid construction.

In addition to providing a construction in which all securing means for holding the parts in an assembled relation are hidden, as in the case of bumper sections 98, the supporting and securing construction for the bumper sections 104 and 106 are likewise concealed. These refinements in construction give a very pleasing effect to the eye and are very much in keeping with present day trend in design.

As it is impractical to place the on and off switch on the operating handle through which the nozzle is manipulated over the surface to be cleaned, it is the practice to locate the motor switch upon the housing of the sweeper structure where it may be manipulated by the foot. The arrangements that have been heretofore proposed have not been entirely satisfactory for the reason that the switch has received considerable abuse from foot manipulation. In my construction I have provided what might be termed a protective shell for the switch proper which at the same time becomes an operating lever facilitating the operation of the switch as it affords a considerable area upon which pressure may be applied for turning the switch on and off.

Having described my invention, what I desire to protect by Letters Patent and claim is:

1. A vacuum sweeper of the type described comprising an elongated tube, reinforcing structure located at opposite ends of said tube having

shoulder portions and portions with which opposite ends of said tube telescope, an air pump and motor unit adapted to be concentrically supported within said tube having a mounting ring structure, said mounting structure being located between one of said shoulder portions and one end of said tube, and tie rods extending longitudinally of said tube and anchored in said reinforcing structure at opposite ends of said tube for holding the elements in assembled relation and for clamping said mounting structure in position between a shoulder and an end of said tube.

2. A vacuum sweeper of the type described comprising an outer fibrous elongated tubular portion, a metal head portion located at one end of said tube, a metal flange portion located at the opposite end of said tube, tie rods extending longitudinally of said tube and located upon the outside thereof anchored at opposite ends to said head and flange portion for securing said elements in assembled relation, and bumper portions supported upon said tie rods.

3. A vacuum sweeper as described in claim 2 wherein the exposed portions of said tie rods are entirely housed by said bumper portions.

4. A vacuum sweeper of the type described comprising a central tubular portion, a pair of heads closing opposite ends of said tubular portion, a plurality of tie rods extending longitudinally of said tubular portion disposed on the outside thereof for securing one of said heads to one end of said tubular portion, the other of said heads being removable to afford access to the interior of said tubular portion, said other head in position concealing one end of said tie rods and the other end of said tie rods being anchored in said first head, and bumper means supported by said tie rods and disposed on the outside of said tubular portion for concealing the exposed length of said tie rods.

HENRY A. KROENLEIN.
